UNITED STATES PATENT OFFICE.

GARLAND F. KIGHT, OF NORFOLK, VIRGINIA.

WHEEL-FACING MACHINE.

1,371,791.

Specification of Letters Patent.

Patented Mar. 15, 1921.

Application filed April 9, 1920. Serial No. 372,619.

To all whom it may concern:

Be it known that I, GARLAND F. KIGHT, a citizen of the United States, and a resident of Norfolk, in the county of Norfolk and State of Virginia, have invented new and useful Improvements in Wheel-Facing Machines, of which the following is a specification.

My invention is a wheel facing machine and is designed for the purpose of facing of the hub of the wheel truly with the wheel rim.

Further, I provide a machine for planing or facing the hub so that the inner and outer faces of the wheel rim will be exactly parallel with the opposite faces of the hub.

Another important object of the invention resides in the provision of a rotatable table upon which the wheel to be faced or trued is mounted and a facing blade or cutter which is automatically advanced across the face of the hub during the rotation of the table, thereby facing or planing the entire surface of the hub level.

It is also within the provisions of the present invention to provide a combined hub facing and wire wheel truing machine wherein the mechanism is such as to be momentarily interchanged for operating upon the hub of a wooden wheel or to true a wire wheel.

My invention further embodies a rotatable wheel supporting table and a cutter or planing element which is advanced step by step across the face of the hub to cut or plane the hub at a different point after each revolution of the table, this being accomplished through the instrumentality of a mechanism actuated by the table rotating mechanism.

It has also been my endeavor to improvise a machine possessing the preceding features and others that may be outlined in the following specification and at the same time provide a machine which is comparatively simple in construction and may be manufactured and sold at a nominal cost.

The invention, as reduced to practice, consists in the combination of elements, construction and arrangement of parts, operations and specific details which will be hereinafter enlarged upon and recited in the subjoined claims and illustrated in the attached drawings wherein—

Figure 1 is a side elevation of a wheel hub facing machine constructed in accordance

with my invention and illustrating the same in operation;

Fig. 2 is a top plan view of the machine;

Fig. 3 is a modified embodiment of the invention, the same being adapted to truing wheels provided with wire spokes; and

Fig. 4 is a detail view of the tool holder and cutter embodied in the construction illustrated in Figs. 1 and 2.

Referring in detail to the drawings, wherein like characters of reference designate like parts throughout the several views, the numeral 5 designates a stand supported by legs 6 engaged in sockets 7 depending from the under face of the stand 5.

Extending vertically from the stand 5 and at the center thereof is a fixed shaft or standard 8. Disposed above the stand 5 is a circular turn table 9 provided with a central opening 10 through which the shaft 8 extends. Extending radially from the turn table 9 is a plurality of outstanding arms 11 carrying clamping elements 12 adapted to engage the rim of the wheel designated R and supported by the arms 11, the shaft 8 extending through the usual hub sleeve receiving opening in the wheel. Mounted upon the under face of the table 9 at its center is a bevel gear 13 revolvable about the shaft 8.

A horizontal bar 14 extends outwardly from the stand at one side thereof and supported upon the outer end of this bar is a vertical bar 15. A shaft 16 has one end journaled in the bar 15 adjacent its lower end and its opposite end journaled in a bearing 17 arranged at the inner end of the bar 15 and rotatable with the shaft 16 is a bevel gear 18 meshing with the bevel gear 13. A crank arm 19 is fixed to the outer end of the shaft 16 for transmitting power to the gear 13 to rotate the table 9. A horizontally disposed guide bar or track 20 is disposed directly above the table 10 and in parallelism with the bar 14, this bar being rectangular in cross section and terminating in ears 21, one of which is engaged upon the upper end of the shaft 8 and is retained thereon by a nut 22 threaded upon this shaft. The opposite end is engaged upon the reduced threaded end 23 of the vertical bar 15. A nut 24 is threaded upon this reduced end and retains this end of the bar rigid with the bar 15.

A tool holder or carriage 25 is provided which tool holder or carriage is formed

from an elongated block of metal and is provided with a transverse rectangular opening 26 at its upper end which receives the bar 20 and is movable longitudinally of this bar. A vertical groove 27 is formed in one face of this tool holder and held in this groove for vertical adjustment is a cutter or facing tool 28.

In order to advance the carriage or tool holder 25 step by step after each complete revolution of the rotatable table so that the entire surface of the hub will be faced, there is provided a horizontally disposed threaded shaft 29 which passes through a threaded bore 30 extending parallel to the opening 26 in the tool holder 25 and has its outer end journaled in the bar 15 adjacent its upper end. A star-wheel 31 is fixed to the outer end of the shaft 29 and adapted to engage the radial pins of the star-wheel 31 is a laterally disposed lug 32 extending from the inner face of the crank arm 19 at its free end whereupon each revolution of the crank arm the star-wheel will be rotated 25 a quarter turn to advance the tool holder across the surface of the hub.

Referring to the wire spoke wheel truing machine illustrated in Fig. 3 there is illustrated a frusto-conical member 33 rotatably mounted upon a fixed vertical shaft 34 upon the stand 5. Extending vertically from the upper face of the frusto-conical member 33 and at its center is a threaded stem 34'. As illustrated in the drawing the frusto-conical hub of the wheel is received on the frusto-conical member 33. A circular nut 35 is threaded upon the stem 34' and has its lower end beveled, as indicated at 36, to fit within the smaller end of the hub of the wheel. With the parts in this position and upon tightening the nut 35 the hub will be forced home and retained in this position until the spokes are tightened in the usual manner. In order to judge whether the rim 45 of the wheel is true with the hub a gage blade 37 is pivoted to the bar 15 adjacent the upper end thereof and in using the gage blade it is swung to a horizontal position to contact with the wheel rim as illustrated in Fig. 3.

It is to be understood that the form of my invention herein shown and described is to be taken as a preferred example of the same, and that various changes in the 55 shape, size and arrangement of parts may be resorted to without departing from the spirit of the invention or the scope of the subjoined claims.

Having thus described my invention, 60 what I claim as new and desire to secure and protect by Letters Patent of the United States is:

1. In a hub facing machine, a rotatable wheel supporting table, means for rotating the latter, and a facing tool movable across

the face of the hub of a wheel supported on the table and advanced step by step after each complete revolution of the table by the table rotating means.

2. In a wheel facing machine, a revoluble 70 wheel support, means for rotating the latter, a facing tool mounted above the support and movable at right-angles to the path of rotation of the support and operated by the rotating means. 75

3. In a wheel facing machine, a rotatable wheel support, a facing tool movable across the face of the hub of the wheel carried by the table step by step subsequent to each revolution of the rotatable wheel support, 80 and means to impart such movement to the facing tool.

4. In a wheel facing machine, a rotatable table, a horizontal bar supported above the table, a carriage movable longitudinally of 85 the bar, a cutting tool rigid with the carriage for facing the hub, a shaft having threaded engagement with the carriage, means for rotating the table, means operated by the table and rotating means for intermittently moving the carriage on the bar. 90

5. A wheel facing machine including a revoluble wheel supporting table, a horizontally disposed bar supported above the table, a carriage having slidable engagement with the bar, a screw shaft for moving the carriage longitudinally of the bar, a facing blade carried by the carriage, and means operated at predetermined times by the table rotating means for rotating the 100 screw shaft to move the carriage to a different position. 95

6. A machine of the character described comprising a shaft, a rotatable wheel supporting table mounted thereon, means for 105 rotating the table, a facing tool movable at right-angles to the direction of travel of the table, and means for intermittently advancing the facing tool across the face of the hub by the table rotating means. 110

7. A wheel facing machine including a stand, a vertical shaft mounted thereon, a table rotatable on the shaft, elements carried thereby for retaining a wheel in true alinement on the table, a vertical bar supported at one side of the table, a horizontal bar having one end supported by the vertical bar and its opposite end secured to the upper end of the shaft, a carriage provided with a transverse opening receiving the 120 horizontal bar, a hub facing element carried by the carriage, the carriage being capable of longitudinal movement thereon, a screw shaft passing transversely through the carriage, means for rotating the table, 125 and means operated by the table rotating means to rotate the screw shaft at predetermined times.

8. A wheel facing machine including a supporting stand, a rotatable wheel sup- 130

- porting table supported thereon, a bevel gear fixed to the under face on the table, a drive gear meshing therewith, a crank arm operatively connected with the drive gear, 5 and a hub facing tool movable intermittently at right-angles to the path of movement of the table, and means operated at each complete revolution of the crank arm to actuate the carriage.
- 10 9. A machine of the character described, a vertical shaft, a rotatable table supported thereon, a gear fixed to the under face of the table through which the shaft passes, a horizontal bar supported below the table, 15 a bearing supported at the inner end thereof, a vertical bar secured to its outer end,
- a shaft journaled through the vertical bar and bearing, a drive element carried thereby and engaging the gear, a crank arm fixed to the outer end of the shaft, a horizontal 20 bar having one end secured to one end of the vertical shaft and its opposite end secured to the vertical bar, a tool holder slidably mounted on the latter, a hub facing tool carried thereby, a screw shaft having 25 threaded engagement with the tool holder and having one end journaled in the vertical bar, a star-wheel carried thereby, and a laterally disposed lug carried by the free end of the crank arm and in the path of the 30 star wheel.

GARLAND F. KIGHT.
